Patented June 6, 1916.

UNITED STATES PATENT OFFICE.

EMMANUEL DOBROWSKY, OF NEW YORK, N. Y.

CIGARETTE-CASE.

1,186,530.

Specification of Letters Patent. Patented June 6, 1916.

Application filed February 14, 1914. Serial No. 818,701.

To all whom it may concern:

Be it known that I, EMMANUEL DOBROWSKY, a subject of the Czar of Russia, and a resident of the city of New York, borough 5 of Brooklyn, in the county of Kings and State of New York, have invented a new and Improved Cigarette-Case, of which the following is a full, clear, and exact description.

10 My invention relates to cigarette cases of the magazine type; and the object thereof is to provide a simple, convenient, compact, inexpensive and attractive cigarette case with which by a simple manipulation of the 15 hand holding the cigarette case a lighted cigarette may be presented ready to be picked up by the lips. I attain this object by the device illustrated in the accompanying drawing forming part of the specification, in which similar characters of reference indicate corresponding parts in all 20 the views and wherein:

Figure 1 is a perspective view of a cigarette case embodying my invention; Fig. 25 2 is a longitudinal, vertical section through the closed case; Fig. 3 shows a similar section through the open case; Fig. 4 is a section on line 4—4, Fig. 2; Fig. 5 is a section on line 5—5, Fig. 2; Fig. 6 is a section on 30 line 6—6, Fig. 2; Fig. 7 shows a plane view of the magazine; and Fig. 8 is an elevation of the latch for locking the feeding table.

Referring to the drawings, 9 represents the main portion of the case which is provided with a hinged cover or section 10. The hinge 11 has a resilient member tending normally to separate the cover 10 from the main portion 9 of the case. The cover is maintained in closed position by means 35 of catches 12 (see Figs. 2, 3 and 6) provided on the main portion 9 and adapted to engage projections formed on the cover 10, said catches 12 being controlled by buttons 13 provided on each side of the main portion 9. (see Fig. 1). The bottom of the main portion 9 of the case is partly cut out, as shown at 14, through where a cigarette magazine 15 can be inserted or removed from the main portion 9 of the case. The 40 magazine 15 is open at the top, and adjacent its bottom at each side thereof it is provided with resilient members 16 adapted to engage the sides of the portion 9 of the case and lock said magazine in place when the same is 45 fully inserted into said portion of the case. It is evident that for the purpose of locking

the magazine in the portion 9 of the casing one resilient member 16 is sufficient but for the sake of symmetry two of said members are provided.

60 A table 17, mounted to slide in grooves 18 provided in the end walls of said magazine, is constantly forced toward the open top of the magazine by means of a collapsible Z-shaped member 19, which is positioned between the bottom of the magazine and said table. The Z-shaped member is provided with resilient members 20 tending to increase the height of said Z-shaped member and thus force the table 17 toward the open 70 top of the magazine.

When cigarettes are to be placed in the magazine, the same is removed from the portion 9 of the case by compressing the resilient members 16 and pulling thereon. 75 The table 17 is then brought toward the bottom; and by means of latches 21 provided on the end walls of the magazine, the said table is locked in its lowermost position, thus permitting the filling of the magazine with cigarettes. At the open top of the magazine stops 22 are provided, each of 80 said stops having a resilient extension secured to one of the sides of said magazine. Said stops prevent the table 17 from ejecting the cigarettes when said table is released by latches 21. When the magazine filled with cigarettes is replaced in the portion 9 of the case, the said stops 22 are forced away from the sides of the magazine 15 by the 85 engagement of a U-shaped member 23 with pockets 24 of the resilient extensions carried by the cover 10 (see Figs. 2, 3 and 5), thus permitting the table 17 to force the cigarettes toward the cover 10. This movement 90 of the table with the cigarettes brings the upper cigarette into engagement with a grip 25 carried by said cover, said grip being formed of two hinged members carried by the cover and springs 26 secured to the cover and tending to force said members toward each other, their movement toward each other being limited so that the said grip cannot be closed more than what is 95 shown in Fig. 4, but it is self-evident that it can open enough to admit a cigarette therebetween. The distance of this grip from the magazine is such that when one cigarette is engaged by said grip 25 the following cigarette is slightly below the stops 22 100 and, therefore, when said cover 10 is opened, the cigarette following the one engaged by

110

the grip will remain in the magazine, due to the disengagement of the U-shaped member 23 from the pockets 24 of said stops 22, thus causing said stops to engage the following cigarette and prevent the movement 5 of the table 17 in the magazine.

The cover 10, at the free end is partly cut away, as shown at 26, so as to present the end of a cigarette carried by the grip 25, as best shown in Fig. 2, whereby the cigarette can be picked up directly by the 10 lips and pulled out of the grip 25. A cap 27 is pivotally mounted on a portion 9 of the case so as to cover said cut-away end 15 of the cover when the said cover closes the portion 9 of the case. The other end of said cigarette engaged by the grip 25 is disposed adjacent a wick 28 projecting from a fuel receptacle 29, which receptacle is provided in said main portion 9 of the case. A plug 20 30 is provided in the bottom of the portion 9, forming the fuel inlet to said receptacle 29. The wick 28 is normally covered by a tubular member 31. The opening of the 25 cover 10 disengages the tubular member from the wick and permits the setting on fire of the same by the frictional engagement of a ratchet 32 and a pyrophoric member 35. The said ratchet is mounted to rotate on an axle 33 carried on brackets 34 which are secured to the sides of the portion 30 9 of the case adjacent the hinge 11. The ratchet is provided with a clutch face 36 engaged by a similar face 37 through the medium of a coil spring 38 mounted on the axle 33. Said face 37 is provided with an arm 39, at the end of which a slot 40 is provided, and which slot is engaged by a bar 41 carried by the cover 10. When the cap 27 is 35 40 swung to disengage the cover 10 and the buttons 13 are pressed toward each other, the catches 12 release the cover 10 and permit the resilient member on the hinge 11 to force the cover away from the portion 9 of the 45 case. This movement being rapid causes a sparking between the ratchet 32 and the member 35, setting the wick 28 on fire as the tubular member normally inclosing the same uncovers the said wick. The burning 50 wick remains stationary while the moving cover brings the cigarette which is engaged by the grip 25 over said burning wick, thus lighting said cigarette, which can then be pulled out of the grip 25 by engaging the 55 projecting end of the cigarette with the lips. When the cover is brought to its normal, closed position, the tubular member 31 will extinguish the flame. The return movement of the cover will not rotate the ratchet 60 32, due to the clutch structure as described. Furthermore, when the cover 10 is returned to its closed position, the U-shaped member 23 will engage the pockets 24 of the stops 22 and force them apart so as to permit the 65 table 17 to force the cigarette toward the

cover and thereby engage another cigarette in the grip 25, making it ready for the next action.

The member 35 is preferably mounted in a socket 42, in which socket a resilient member 43 is provided which forces said member 35 into engagement with the ratchet 32. A plug 44 is provided in the portion 9 of the case which closes the socket 42 and through where the resilient member 43 and the member 35 are inserted.

It will be seen that with a case as described, a cigarette can be presented to the lips, lighted ready for use, without handling. That is, the entire operation can be 80 performed by the same hand which holds the case by simply swinging the cap 27 away from the cover 10 and then pressing the buttons 13, thus presenting a lighted cigarette ready to be picked up by the lips. 85

Having thus described my invention, I claim as new and desire to secure by Letters Patent:

1. The combination of a cigarette case having a cover with a lighter, said case and 90 cover having coating means adapted to ignite the lighter when the cover is opened, said cover having means adapted to pick up a cigarette from the case when opening the cover, exposing one end thereof, while the 95 other end of the cigarette is presented to the flame of the lighter.

2. A cigarette case having a cover; means on said cover adapted to pick up a cigarette from the case; and means in said case to 100 light one end of said picked-up cigarette when the cover is opened, said cover being adapted to expose the other end of the cigarette substantially as and for the purpose set forth.

3. A cigarette case having a cover; a cigarette magazine removably associated with the case; means in said magazine for feeding cigarettes to the cover; a lighter in said case adapted to be lighted when said cover is raised from the case; means in said cover adapted to pick up a cigarette from the magazine; and resilient means for raising the cover whereby the same presents one end of a cigarette to the lighter, leaving the other end free, substantially as and for the purpose set forth. 110 115

4. A cigarette case having a cover; a cigarette magazine removably associated with said case; means in said magazine for feeding cigarettes to the cover; means in said magazine controllable by said cover whereby the feeding means of the magazine is controlled; a lighter in said case adapted to be lighted when said cover is raised; means in said cover adapted to pick up a cigarette from the magazine; and controllable resilient means for raising said cover from the case whereby a cigarette picked up by the cover has one end presented to the 120 125 130

lighter and the other end exposed free to be picked up.

5. A cigarette case having a cover; a cigarette magazine removably associated with the case; a table in the magazine adapted to support the cigarettes; means for moving the table toward the cover whereby the cigarettes are fed thereto; stops carried by said magazine preventing the feeding of cigarettes to said cover; means carried by the cover controlling said stops whereby cigarettes are fed to said cover only when the same is closed; means carried by said cover adapted to receive and retain a cigarette; a lighter in said case adapted to be lighted when said cover is raised; and controllable resilient means for raising said cover whereby a cigarette picked up by the cover has one end presented to the lighter and the other end exposed free to be picked up.

6. A cigarette case having a cover; a cigarette magazine removably associated with the case; means in said magazine for feeding cigarettes to the cover; resilient stops on said magazine normally preventing the feeding of cigarettes to the cover; a U-shaped member carried by the cover adapted to engage said resilient stops when said cover is closed, thereby permitting the feeding of cigarettes to the cover; a grip carried by said cover and adapted to receive a cigarette fed by the means from the magazine; a lighter in said case adapted to be lighted when said cover is raised; and controllable resilient means for raising said cover whereby the cigarette engaged by the grip has one end presented to the lighter and the other end exposed free to be picked up.

7. A cigarette case having a hinged cover, the unhinged end of which is partly cut

away; a cup associated with said case adapted to normally mask the cut-away end of said cover; a cigarette magazine removably associated with the case; means in said magazine operable by said cover whereby the cigarettes are fed to the cover; means in said cover adapted to pick up a cigarette from the magazine; a lighter in said case adapted to be lit when said cover is raised; and operable resilient means for raising said cover from the case whereby a cigarette picked up by the cover has one end presented to the lighter and the other end exposed at the cut-away end of said cover.

8. A case for cigarettes, a cover therefor, means for normally holding said cover in closed position, means for releasing said cover, means for opening the same, and means for removing a cigarette bodily from said case when said cover is opened.

9. A case for cigarettes, a cover therefor, means for normally holding said cover in closed position, means for releasing said cover, means for opening the same, and means for removing all the cigarettes in said case bodily from said case successively, on successive cover openings.

10. A case for cigarettes, a cover therefor, means for normally holding said cover in closed position, means for opening said cover, a lamp secured in said case, means for igniting the same in the opening of said cover, and means for carrying a cigarette to ignition position adjacent said lamp in the opening of said cover.

In testimony whereof I have signed my name to this specification in the presence of two subscribing witnesses.

EMMANUEL DOBROWSKY.
